UNITED STATES PATENT OFFICE

PHELPS BROWN AND TERRENCE G. LOUIS, OF SPRINGFIELD, MASSACHUSETTS, AS
SIGNORS TO WICO ELECTRIC COMPANY, OF WEST SPRINGFIELD, MASSACHUSETTS, A
CORPORATION OF MASSACHUSETTS

MAGNETO

Application filed April 9, 1928. Serial No. 268,706.

This invention relates to improvements in magnetos.

The magneto is an improvement on that disclosed in the copending application of Phelps Brown, filed March 24, 1926 under Serial No. 97,011. The magneto of said application includes a driving mechanism by means of which the armature can be moved away from its poles in either of two ways, viz, entirely by an inelastic transmission of force or initially by such a transmission followed up by an elastic transmission of force due to the expansive effort of a previously stressed drive spring. Such magneto also includes provisions for opening the primary circuit after the armature has been seated on its poles and for holding said circuit open for an interval while the armature is in contact with its poles, for the purpose of allowing the flux to build up rapidly in the magnetic circuit.

The present invention, among other things, is directed to the elimination of the last named provisions and certain complications which follow from the use of such provisions. This change, however, results in the disadvantage that the flux cannot be built up in the circuit under as favorable conditions as formerly. That is, the primary circuit, which remains closed while the armature is in contact with its poles, exercises a restraining influence on change of flux in the magnetic circuit, wherefore the flux builds up more slowly in the magnetic circuit. Under such conditions, the armature actuating mechanism of the prior application is not satisfactory in so far as the advance or high speed drive is concerned. Therefore, one of the problems with which this invention is concerned is the development of an armature actuating mechanism which will afford a satisfactory advance or high speed drive under the aforesaid condition.

According to this invention, the armature actuating mechanism for the advance or high speed drive has been changed from that of the aforesaid application in such ways as to introduce factors which offset the disadvantage due to building up flux against a closed circuit primary winding. These factors are increased time for the building up of the flux

and increased speed in the early stage of the armature movement. The first factor results from arrangements which permit the armature to remain in contact with its poles for a substantial interval. The second factor results from the injection into the former advance drive, which was solely by inelastic transmission, of a spring impulse occurring in the early stages of the armature flight and directly following the unseating of the armature from its poles.

While the advance or high speed drive is broadly similar to the retard or starting drive, the fact is that they are not equivalent. The high speed drive would not be effective at cranking speeds and the starting drive would not be suitable for high speed work, notwithstanding that each utilizes a spring impulse. This is explained from the fact that the impulse of the spring is added to the kinetic energy imparted from the drive shaft. In high speed work, the spring is moving rapidly at the time when it expands and produces the impulse, while at cranking speeds the drive shaft turns so slow that no material kinetic energy is imparted to the spring, and the spring impulse has to be relied on to do all the work. Thus, the spring impulse used for starting would, if used for high speed, be too violent and produce overthrow of the armature while the spring impulse used on the high speed drive would, if used for starting, be insufficient to move the armature fast enough. Accordingly, it is necessary to have different degrees of spring impulse.

To secure the requisite degrees of spring impulse for the two different operating conditions necessitates another change which consists in the use of a drive spring initially stressed to a substantial degree, as distinguished from the substantially unstressed drive spring of the prior application. The two parts, between which the spring is interposed, have to engage and effect the inelastic transmission for the armature tripping function at an earlier time for the high speed drive than for the starting drive, which means that much less relative movement of these parts is available on the high speed drive. So little

of such relative movement is available that an initially unstressed drive spring would not be stressed enough for the work in hand and the armature, in the initial part of its flight, would lag to such an extent that it would not effect separation of the breaker points at any earlier time than with the starting drive, notwithstanding that the armature started earlier. It is necessary not only to start the armature in its flight at an earlier time but also to make it reach the breaker point opening position at an earlier time.

The invention has other features relating to improvements in various parts of the magneto other than the armature actuating mechanism. These features can best be set forth in the following description and they will be particularly pointed out in the appended claims.

The invention will be disclosed with reference to the accompanying drawings, in which:-

Figs. 1, 2 and 3 are small scale exterior elevational views showing the rear and the left and right ends, respectively, of the magneto;

Fig. 4 is a sectional elevational view taken on the line 4—4 of Fig. 3;

Fig. 5 is a bottom plan view, showing the magneto as it appears when the lower housing is removed and showing the armature driving mechanism in one of its two operating positions;

Fig. 6 is a fragmentary bottom plan view, taken similarly to Fig. 5 but showing the armature driving mechanism shifted into its other operating position;

Fig. 7 is a cross sectional view, taken on the line 7—7 of Fig. 4 and illustrating the armature driving mechanism;

Fig. 8 is a sectional elevational view taken on the line 8—8 of Fig. 3;

Fig. 9 is a top plan view showing the magneto as it appears after the cap has been removed;

Fig. 10 is a sectional view taken on the line 10—10 of Fig. 8;

Fig. 11 is a cross sectional view taken on the line 11—11 of Fig. 1; and

Fig. 12 is a fragmentary cross sectional view taken on the line 12—12 of Fig. 5.

The magneto includes a source of magnetic flux (Fig. 4) which comprises a series of short bar magnets 15; a magnetic circuit from said source, comprising two cores 16 connected one to each polar extremity of said source, and an armature 17 which is pivotally supported for movement to and from the lower ends of the cores; mechanism for reciprocating the armature from a rotary drive shaft 18; electrical windings comprising two primary coils 19 and two secondary coils 20; an interrupter mechanism comprising cooperating and relatively movable breaker points 21 and 22 (Fig. 11) adapted to be separated by armature 17 at a predetermined point in its flight away

from cores 16 to open the normally closed primary circuit in which coils 19 are included, thereby inducing an electromotive force in the secondary coils; and a condenser 23 associated in the usual way with the interrupter. The armature driving mechanism includes a starting or low speed drive and a normal or high speed drive and is also so arranged that a retarded spark is secured with the first form of drive and an advanced spark with the other form of drive. The selection of the particular form of armature drive desired is made by shifting a lever 24 and the movement of this lever also controls the timing of the spark.

All parts of the magneto, except for lever 24, part of drive shaft 18 and certain electrical terminals, later to be described, are encased by three members A, B and C, as will be plain from Figs. 1, 2 and 3. The member A, as shown, is a one piece molded member of bakelite, or other suitable material. In

this member substantially every part of the magneto is assembled, after which the parts B and C are applied to the lower and upper ends, respectively, of member A to house in the parts, which project beyond such ends. The member C is a pressed metal cap adapted to tightly fit about the top of member A, as indicated in Fig. 4. The member B is a hollow metal base, much like a crank case, which in addition to housing the armature and its driving mechanism, also serves to contain the supply of lubricant and the means for distributing the same to the various moving parts. The member A rests upon the top of the upstanding marginal walls of member B and a gasket 25 (Fig. 7) partially imbedded in a groove in said top, seals the joint between the abutting parts. The parts A and B are held together by a pair of studs 26 (Figs. 4 and 5) and a cap screw 27 (Figs. 4 and 11). The latter passes upwardly through base B and threads into a metallic insert 28 in member A. One end of each stud 26 is imbedded in the member A during the process of molding of the same. These studs depend from member A on opposite sides of the drive shaft 18 and pass through openings in one end wall of base B. Nuts 29, threaded on the lower ends of studs 26, serve to draw the parts A and B together.

Referring now to the electrical windings, these are housed within the bakelite member A, which is provided with a pair of openings extending vertically therethrough for that purpose. These openings, as shown in Fig. 4, are larger at the top than at the bottom leaving annular horizontal shoulders 30, on which the secondary coils 20 rest. There are also shoulders 31 which serve to support the primary coils. One secondary coil (that on the left in Fig. 4) has, as one terminal, a copper strap 32 which passes upwardly out of the coil receiving recess. One terminal of the

other coil is connected to the high tension terminal button 33 of the magneto. The inner end of this button is received in a recess in the outer wall of member A and is secured thereto by a hollow rivet 34, prior to the insertion of the secondary coil. The terminal wire 35 of this coil is pushed through the hollow rivet, as the coil is set in place in its recess, and the wire is afterwards soldered to the button near its outer end. The two secondary coils are connected together by a wire 36 which is covered by an insulating strip 37. The member A is provided with a groove 38 (see also Fig. 11), extending between the coil receiving openings, to receive the wire 36 and strip 37. Each primary coil 19 is wound on a tubular core 39 and then set into a cup 40. The latter has an opening in its base of the proper diameter to receive the lower end of core 39 which terminates flush with the base of the cup. This cup is slipped through the secondary coil 20 and its base rests on shoulder 31. The upper end of each cup is filled with a suitable sealing compound, indicated at 41. Each cup has an outwardly turned flange 42 which overlies the top of the adjacent secondary coil and closes off the opening in member A, except for a small annular space through which strip 32 passes. This space is then filled with sealing compound as indicated at 43. Sealing compound may also be applied at the base of each cup 40, as indicated at 44. The lead wires for the primary winding are shown at 45 and 46 and the two coils of this winding are connected together by a wire 47.

The member A, at a point midway between its coil receiving recesses but near its back wall, is provided with a cylindrical recess 40 open at the top, into which the condenser 23 (of roll form) is placed, as shown in Fig. 11. The terminals of the condenser (a short bare copper strip 48 and an insulated wire 49) are led upwardly out of the recess and the upper end thereof is suitably sealed, as indicated at 50.

Disposed near the front wall of member A and opposite the condenser receiving recess is a cylindrical recess 51 which extends upwardly from the base of member A but terminates short of the upper wall thereof. Inset into the closed upper wall of recess 51 is a metallic piece 52, which is threaded to receive a stud 53. The latter, at its lower end, carries the fixed breaker point 21 and its upper end is provided, as shown, with a screw slot, whereby the breaker point 21 may be vertically adjusted when cap C is removed. A lock nut 54 serves to preserve the adjustment of the fixed breaker point and also to hold in place the terminal piece 55. The latter has a down-turned lug 56, which enters a hole 57 in member 52 and thereby holds piece 55 from turning. The hole 57 serves to vent the recess 51 to the interior of cap C,

which as will appear is vented to the atmosphere. The other terminal 22 of the interrupter is carried by a plunger 58 having two axially spaced bodies 59 of felt or the like, which slidably engage the bakelite wall of cylinder 51 and require no lubrication. The lower end of plunger 58 has a flange 60, which is engaged by a spring 61. The latter, one end of which is frictionally held in a hole in base A, tends to hold the breaker points 21 and 22 in engagement. An opening, leading from the front wall of member A and intersecting recess 51, is provided to permit inspection of the breaker points. This opening is normally closed by a cup-like part 62 which snugly fits, and is frictionally held in place, in the opening.

The stationary members of the magnetic circuit are first assembled and then applied as a unit to the member A. Each core 16 is made up of laminations and these laminations are bound together in any suitable way, as by a rivet 63 (Fig. 4) near its lower end and a bolt 64 near its upper end. The lower extremity of each core, which constitutes a polar face adapted to be engaged by armature 17, is of somewhat less cross sectional area than the body of the core, thereby intensifying the flux at such polar face. The cores 16 are provided near their upper ends with confronting recesses in which the polar extremities of the bar magnets 15 are received. These magnets are suitably held in said recesses, as by wedges 65, which are driven in between two adjacent magnets of the stack. The two cores 16 are tied together by a pair of cross bars 66 (Fig. 9) which are held in place by the bolts 64, above described. Each of these cross bars has an outwardly turned horizontal flange 67 which is adapted to rest upon the upper face of member A (Fig. 11) and to be secured thereto by cap screws 68. The flanges 67 are centrally recessed to allow access to the condenser and the upper terminal of the interrupter.

After the cores, magnets and cross bars have been assembled, this unit is slipped in place by passing the cores downwardly into and through the spools 39 of the primary coils. This unit is properly located relatively to block A by the abutment of the lower magnet 15 with seats 69 (Fig. 11), provided in the upper face of member A, and by the abutment of the flanges 67 with said face. Prior to slipping cores 16 into spools 39, the secondary ground terminal 32, a strip of bare copper, is bent downwardly (Fig. 4) so as to lie in the bore of the left hand spool and so as to lie at an acute angle to the axis of said bore and in the path of the left hand core 16. Then, when the latter is pushed into place, it engages and flexes the spring end of terminal 32, whereby said terminal is grounded to said core. The ground terminal 48 of the condenser is bent so as to underlie one of

the flanges 67 (Fig. 9) and become electrical-
ly connected thereto when the cap screws 68
are applied. Having applied these four caps
screws, the magnetic field unit is securely
fixed to member A.

The electrical connections of the primary
circuit are then completed. The terminal
wire 45 and the lead wire 49 of the condenser
are connected to the terminal 55 of the inter-
rupter (Fig. 9). The primary terminal wire
46, as well as a ground wire 70, are connect-
ed to a terminal 71 which is secured by one of
the cap screws 68 to one of the flanges 67.
The ground wire 70 (Figs. 5 and 9) passes
downwardly through the spool 39 of the
right hand primary coil. The cores 16 are
of square cross section, except that their
edges are chamfered. Consequently, when
the cores are placed in spools 39, four pas-
sages 72 are left between each core and its
spool. These passages extend from the base
to the top of member A and afford ventilat-
ing ducts for the hollow base B. One of
these passages also serves as a conduit for
the ground wire 70.

On the base of member A (Figs. 5 and 12)
is a stud 73 having a nut 74 by means of which
a spring contact 75 and a terminal piece 76
are clamped in place. The wire 70 is secured
to terminal 76. When the housing B is put
in place, one of its side walls engages and
flexes the spring contact 75, whereby a good
ground connection is had to base B (the part
which is adapted to be bolted to the engine).
It is to be noted that the ground wire 70 af-
fords a good electrical connection directly
to the grounded terminals of the primary, sec-
ondary and condenser, and that the ground
circuit path does not include any moving
parts of the magneto. The ground connec-
tion for the interrupter is made directly to
base B by means of spring 61 (Fig. 11)
which constantly engages the plunger 58 to
which breaker point 22 is secured. This
plunger is periodically moved downwardly
by a lug 77 fixed to armature 17 and this lug
is insulated from the armature by suitable
means including the strip 78 so as to exclude
the armature from forming any part of the
path of the ground circuit. Heretofore, when
the armature has formed part of such path, it
has been found that the oil in the armature
hinge bearings has been carbonized. By in-
sulating the lug 77 from the armature, this
difficulty has been overcome.

To avoid the general difficulty of the harm-
ful effect on the lubricating oil by ozone lib-
erated within the closed magneto casing, the
same is fully ventilated. The flues 72 ade-
quately vent the lower housing to the space
within cap C and the interrupter cylinder
51 is likewise vented to said space, as here-
tofore described. To complete the venting
system, a hole 79 is provided centrally in cap
C (Figs. 4 and 11). Overlying this opening

is a curved plate 80, which may be the name
plate of magneto, and this plate is suitably
secured as by rivets, to the indented central
part of cap C, in such a way that a slight
space is left between the plate and cap at
the point where the plate overlies hole 79.
Secured to the inner wall of cap C and under-
lying hole 79 is a piece 81 of spring metal
which is sufficiently spaced from cap C to
allow communication between hole 79 and the
interior of cap C. The plate 80 and piece 81
make it difficult for water or dust or dirt to
enter the magneto. The piece 81 has two de-
pending prongs 82 (Fig. 4). When cap C is
pressed in place, the lower and inturned ends
of prongs 82 engage the bevelled top edges of
cores 16, whereby the prongs are thus flexed
outwardly and guided so that they will slide
down along the vertical outer faces of the
cores. The prongs thus press against such
faces and frictionally hold the cap C in place.

The member A has formed thereon a pair
of axially alined bearings 83 and 84 (Figs.
5 and 8) which depend from the lower face of
the member near the rear wall thereof. These
bearings are provided with metallic bushings
85 and 86 (Fig. 8) suitably fixed in place dur-
ing the process of molding member A. Ro-
tatably mounted in these bearings is a hollow
shaft 87 to which armature 17 is suitably
fixed. As shown in Figs. 5 and 11, the arma-
ture is secured by cap screws 88 to a pair of
blocks 89 and these screws also serve to hold
the lug 77 to the armature as well as to clamp
the laminations of the armature together. 100
Each block 89 is bored to receive shaft 87 and
is slotted, as at 90, and provided with a cap
screw 91, which acts to draw together those
parts of the block which lie on opposite sides
of slot 90 and thus bind the block securely to
shaft 87. One of these blocks (Fig. 8) sub-
stantially abuts an end of bearing bushing 85
and the other substantially abuts the adjac-
ent end of bearing bushing 86, whereby shaft
87 is held within small limits against axial
displacement. The armature is normally
held in contact with the lower faces of cores
16 by magnetic attraction. The breaker
point return spring 61 serves to move arma-
ture 17 upwardly and sufficiently into the
field of magnetic attraction so that the re-
mainder of its upper flight may be completed
by magnetic attraction. 110

The member A (Figs. 4 and 12) is pro-
vided with a bearing 92 depending from its
base and provided with a metallic bushing
93. This bearing receives the small inner end
18' of drive shaft 18. Between the end 18'
and the main body of drive shaft 18 (Fig. 4)
an eccentric 94 is formed thereon, and over
this eccentric is placed a loose ring 95 (see
also Fig. 7), which functions as an anti-fric-
tion roll. Beyond the eccentric is a main bear-
ing bushing 96 (see also Fig. 5), which is
clamped between members A and B of the 125
130

studs 26 and nuts 29, above described. This bushing is provided with a longitudinal groove to receive a key 97 formed on member A, whereby it is properly located angularly and held from turning. Bushing 96 is likewise milled out, as shown in Fig. 5, to form a shoulder 98 which is engaged by a washer 99 fitting tightly on one of studs 26. When this washer is pressed down against the shoulder 98, the bushing will be properly located longitudinally of member A and held against axial displacement. Washer 99 also serves as a convenient means for holding the bushing in place during assembling operations.

The eccentric 94 operates through a pair of levers 101 (Figs. 5 and 7) and 102 to move the armature away from the polar faces of cores 16. These levers are pivotally mounted on armature hinge shaft 87 and are free to turn thereon and free to turn relatively to one another within the small limits necessary. These levers, instead of operating directly on armature 17, are arranged for convenience to operate on an arm 103, which is fixed to shaft 87 and arranged adjacent to the levers 101 and 102. These levers and arm 103 lie in the space between bearings 92 and 96 (Fig. 4), extend transversely of shaft 18 and underlie eccentric 94. The arm 103 (Figs. 5 and 12) is riveted at 104 to one arm of a split hub 105 which is clamped to shaft 87 by means of a cap screw 106. The lever 101 has suitably fixed thereto a hub 107 (Figs. 7 and 8) which is slidable as well as turnable on shaft 87. Lever 102 has fixed to it a similar hub 108 which fits over hub 107. A pin 109 passes diametrically through both hubs 107 and 108 and through a diametrical slot 110 in one end of shaft 87. Hub 107 is slotted at 111 to receive pin 109 and permit the necessary relative turning movement between the hubs. The slot 110 is wide enough to afford enough freedom to pin 109 to permit both hubs to turn on the shaft throughout the desired range. Slot 110 also permits the levers 101 and 102 to be axially shifted from the position shown in Fig. 5 to that shown in Fig. 6. A spring 112, encompassing hub 108, acts between an end wall of base B and lever 102 tending to hold the levers 101 and 102 in the position shown in Fig. 5. The levers 101 and 102, when shifted to the position shown in Fig. 6, are limited in their movement by the abutment of pin 109 (Fig. 8) with a pin 113 which is fixed in shaft 87 and passes diametrically through the latter at right angles to slot 110.

The levers 101 and 102 at their outer extremities have projections 114 and 115 (Fig. 7) which extend inwardly toward one another and are adapted under certain conditions to abut, whereby an inelastic transmission of force from lever 101 to lever 102 may be effected. Between said extremities is a drive spring 116 in opposite ends of which the pro-

jections 114 and 115 are received. This drive spring, when put in place, is under an initial tension of substantial degree. To prevent the tensioned spring from spreading the levers 101 and 102 apart (beyond the limit shown in Fig. 7), a lug 117 is struck out from lever 101 and this lug underlies lever 102 and engages the same for the stated purpose. The arm 103, which moves, and moves with the armature has two lugs 118 and 119 struck out from its lower edge. These lugs, as shown in Fig. 5, are of different width and disposed at different radial distances from shaft 87. The lug 118 is closer to the shaft and of less width than lug 119. When the levers 101 and 102 are positioned as in Fig. 5 (which may be termed the advance or high speed drive position) the lug 118 underlies lever 101; but when these levers are shifted to the retard or starting drive position shown in Fig. 6, lug 118 will no longer lie in the path of the lever 101. The lug 119 is wide enough so that it lies in the path of lever 102 in both positions of this lever. The weight of the levers 101 and 102 normally holds the latter in engagement with lug 119, as shown in Fig. 7.

Assuming that the levers 101 and 102 are in the starting position shown in Fig. 6, the depression of lever 101 by eccentric 94 will cause no movement of lever 102 and arm 103 until the projections 114 and 115 abut. This follows because lug 118 does not lie in the path of lever 101. It is to be noted that drive spring 116, even when fully stressed, is not powerful enough to overcome the force of magnetic attraction, which holds the armature to cores 16 and therefore holds arm 103 in the position illustrated in Fig. 6. Consequently, as lever 101 is depressed by eccentric 94, the arm 103 and lever 102 remain stationary while the tension of spring 116 is increased as lever 101 moves toward lever 102. Continued movement of lever 101 will cause the engagement of projections 114 and 115 and there then results an inelastic transmission of force from the drive shaft through levers 101 and 102 to lug 119 of arm 103, whereby the armature 17 is pried off its poles and started in its downward flight. Once the armature has been separated from cores 16, even by a very slight air gap, the force exerted on the armature by magnetic attraction, is so much lessened as to be inferior to that of the stressed drive spring 116, wherefore the latter expands and rapidly moves the armature.

Assuming that the levers 101 and 102 are positioned as in Fig. 5, then as lever 101 is moved downwardly by eccentric 94, this lever will engage lug 118 before the projections 114 and 115 can engage. This results in increasing the stress of the drive spring 116, but not to so great an extent as before because the levers 101 and 102 move toward one

another only a short distance before lever 101 abuts lug 118. It also results in "tripping" the armature,—i. e., breaking the magnetic hold thereon and initiating the downward flight thereof,—at an earlier point in the revolution of drive shaft 18. Once the armature has been tripped, the drive spring 116 comes into play for a short interval (until the spring moves lever 102 into abutment with lug 117) and moves the armature by means of the lever 102 and abutment 119 of arm 103. Although the drive spring can act only for a short interval, it nevertheless produces, due to its initial stress, a sufficient impulse to accelerate the movement of the armature in the earlier stages of its flight. After spring 116 has thus acted and has spread the levers apart to the limit permitted by lug 117, the remainder of the flight is completed by the action of the eccentric which follows up the momentary spring impulse with a positive drive which is virtually inelastic since spring 116 does not yield.

The driving levers 101 and 102 are shifted from one to the other of the described positions by means controlled by the above described lever 24. The latter is fixed to a cam 120 (Fig. 8), which lies within one end of the hollow shaft 87. Cam 120, when turned, serves to move axially inward a cam follower 121 which slides in a diametrically disposed slot 122 in said end of shaft 87. The follower 121 acts (preferably through a spring 123) to move a rod 124, which is slidable in shaft 87, and the latter abuts the described pin 109 and thus moves the interconnected levers 101 and 102. The shifting of these levers should be effected while the armature is on its poles so that neither lever will be bearing against the lugs on arm 103 under any great pressure. The spring 123 enables the shift to be effected at the proper time irrespective of the time when lever 24 is moved. If, when lever 24 is turned, either lever 101 or 102 is being forced against the lugs 118 or 119, respectively, the spring 123 simply compresses without moving rod 124. Subsequently, when the pressure between the described parts is relaxed, spring 123 will expand and move rod 124 to shift the levers. The shifting of the levers 101 and 102 back from the position shown in Fig. 6 to that shown in Fig. 5 is effected by spring 112 after lever 24 has been moved to permit. Spring 112, like spring 123, will not necessarily effect the shift immediately when lever 24 is turned but the action will be deferred, if necessary, until the pressure between levers 101 and 102 and 103 is relaxed.

Cam 120 has a cylindrical part 125 of less diameter which is rotatable in one end of arm 126. The other end of this arm is fixed by cap screws 127 to an end wall of base B (Fig. 3). Beyond part 125 is a hexagonal part 128 and beyond the latter a threaded end 129. A cupped spring washer 130 is first

placed on part 128 and this is followed successively by a washer 131 and lever 24, after which a nut 132 is applied to the threaded end 128, thus holding the lever 24, washer 131 and cam 120 in place relatively to arm 126. Washer 131 has an ear 133 which is struck outwardly therefrom and which rides in an arcuate recess 134 (Fig. 10) formed in arm 126, and the end walls of this recess limit the movement of lever 24 and define the proper positions of the latter for retard and advance drive. The cam 120, lever 24 and washers 130 and 131 are assembled on arm 126 before the latter is fastened to base B. Then after base B has been put in place, rod 124, spring 123 and cam follower 121 are successively dropped into the hollow shaft 87. Then the cam 120 is slipped into the open end of shaft 87 and arm 126 is fastened to base B. The cam 120 closes the end of shaft 87 and the arm 126 seals this closure, making it difficult for dust and dirt to enter the hollow shaft.

For lubricating the moving parts of the magneto, an absorbent pad 136 (Figs. 4, 8 and 11) is placed in the bottom of the housing B and soaked with oil. Oil may be supplied to this pad through an opening in the housing B, such as that opening which is normally closed by the screw plug 137 (Fig. 1). Oil from this pad is led to the various bearings by wicks, which are preferably reinforced by a metal wire and may be similar in construction to the familiar pipe cleaner. A wick 138 (Fig. 8) leads from pad 136 upwardly through the lower part of bearing 83 and into an annular groove in bushing 85. A wick 139 leads from pad 136 and enters a longitudinal groove in shaft 87, lying between the shaft and bushing 86. A wick 140 leads upwardly from pad 136 into a longitudinal groove in bushing 93 (Fig. 4) and then passes downwardly back to the pad, in such a way that one end face of eccentric 94 and roll 95 bear against the wick. A wick 141 leads upwardly from pad 136 and into a longitudinal groove in the main bearing bushing 96. The latter has a circumferential groove 142 in its outer periphery to collect oil which may creep outwardly and such oil drains to the bottom of the groove and thence to the housing B as shown in Fig. 4.

After the armature and its driving mechanism have been assembled, all of which is accomplished before housing B is applied and while the magneto is inverted, the pad 136 is laid in position resting on top of the armature. The various wicks, which have previously been placed in their respective bearings, are passed through holes in the pad and then bent over on top of the pad. Then the housing B is applied, bolted in place and the magneto righted up so that the pad 136 drops to the floor of the housing with the bent over ends of the wicks therebeneath.

It is to be noted that the armature bearings

85 and 86 are fixed in integral extensions 83 and 84 of the bakelite member A. When, however, housing B is applied, it supports both of these bearings as well as the main bearing 96. The part 84 is grooved out as shown in Fig. 5 to receive the housing B and the bearing 86 which forms the bottom of this groove is received in a semi-circular seat in housing B (Figs. 5 and 8). The latter has an integral upstanding part 143 (Figs. 4 and 8), the upper edge of which forms a supporting seat for member 83. The main bearing bushing 96 is, of course, supported directly by the housing B.

If desired, a terminal 144 (Fig. 11) may be provided on cap C and insulated therefrom. Connected with this terminal inside the cap is a spring wire 147, the free end of which, when cap C is put in place, bears against the insulated terminal 55 of the interrupter. Terminal 144 is provided with a binding nut 145 so that a wire may be connected thereto. Such wire may be used in any suitable way to establish a ground connection when desired for the purpose of short circuiting the primary coils and stopping the magneto.

In operation, the drive shaft 18 is suitably connected to a moving part of the engine so as to be continuously rotated thereby at proper relative speed. Once each revolution, eccentric 94 will engage and depress lever 101, thereby increasing the stress of the drive spring and subsequently prying the armature 17 off its cores. Following the prying off or tripping of the armature, the stressed drive spring moves the armature away from its poles and at a predetermined point in the downward flight of the armature, the armature lug 77 engages the flange 60 of breaker point plunger 58 and causes a separation of breaker points 21 and 22. This opens the hitherto closed primary circuit and an electromotive force is induced in the secondary coils. The spring 61 returns the armature towards its poles far enough so that the remainder of the flight can be completed by magnetic attraction. It will be noted that the breaker points close when spring 61 ceases to move the armature upwardly. Thus, the final part of the upward flight of the armature is made against a short circuited primary which tends to lessen the violence of the final movement of the armature. This arrangement, coupled with the shock absorbing effect of spring 116, enables the armature to be seated on the cores 16 with comparative quietness.

The drive spring, because it is under a substantial degree of initial stress, offers effective resistance against the "sucking in" of the armature by magnetic attraction in the latter stages of its flight toward the cores, whereas a spring which is initially unstressed would not do so. When spring drive

is used, the eccentric 94 does not have full control of the return flight of the armature as it would if the transmission were inelastic. While the eccentric controls the movement of lever 101, the lever 102 may move upwardly at a faster rate because the armature is drawn towards its poles by magnetic attraction and the interposed spring 116 may yield to permit this action. It is important therefore, to use the initially stressed drive spring because it prevents an uncontrolled "suck in" of the armature such as would tend to result in a noisy seating of the armature on its poles. At the same time, the spring can and does yield somewhat which is an advantage because the armature becomes seated on its poles at a slightly earlier time than would be otherwise possible. Thus, the period of dwell of the armature on its poles is lengthened. As will be plain from Fig. 85 7, there is considerable lost motion between the lever 101 and eccentric 94, when the latter is in its uppermost position. The eccentric can be turned through a considerable angle (approaching 180 degrees) without removing the armature from its poles. The dwell interval thus afforded, augmented by that due to the compression of spring 116 both at the start of the downward flight and at the end of the return flight of the armature, allows time for the flux to build up sufficiently even under the unfavorable condition of a closed circuit primary winding.

In view of the unfavorable condition under which the flux is built up in the magnetic circuit, it is desirable to compensate for the disadvantage by resorting to a spring impulse on direct drive. While the long dwell of the armature on its poles also compensates in part for the aforesaid disadvantage, it is usually necessary, or at least desirable, to insure a speedy start of the armature in the early stages of its flight, and this is effected by the spring impulse, characterized in that the drive spring is initially stressed to a substantial degree. The necessity for the initial stress in spring 116 will best appear from a consideration of what happens if one starts with an unstressed drive spring, such as was formerly used for the spring impulse starting drive, and tries to get a spring impulse in the high speed drive and at the same time secure an advance in the timing of the spark. The obvious plan would be to bring the abutments 114 and 115 closer together in an effort to get spark advance on the high speed drive. This would allow some compression of the drive spring and would start the armature from its poles at an earlier time. Experiments in this direction show that no advance in spark is obtained, notwithstanding that the armature starts earlier, because the greatly lessened stressing of the drive spring results in a force, which is inadequate to move the armature fast enough to arrive at breaker- 123 130

point opening position earlier than it did on the starting drive. In other words, to secure spark advance, it is not enough to simply start the armature in motion at an earlier time but means must be provided to insure that the armature arrives at said position at an earlier time. If, however, the spring is always under a substantial initial stress, a substantial force is available to impart a kick to the armature and move it rapidly towards said position so that the desired spark advance is obtained even through the movement of levers 101 and 102 towards one another is limited. Just as soon as the levers 101 and 102 move toward one another even by a small degree, the force of the stressed spring is available to move the armature and, immediately following the prying of armature off its poles, the spring exerts this force and imparts the impulse. This impulse is necessarily of short duration, but it is nevertheless sufficient under high speed drive conditions because the force of the spring is added to that due to the kinetic energy of the rapidly moving levers. Also it should be noted that due to the lost motion between the eccentric 94 and lever 101, the latter will be rapidly moved by the eccentric and suddenly put into motion, as distinguished from the slow initial motion which would occur if the lost motion were not present.

Thus, a speedy movement of the armature is effected which, taken with the long dwell of the armature on its poles, is the key to the solution of the problem of making the magneto operate satisfactorily on high speed drive under the unfavorable condition due to building up flux against a closed circuit primary winding. By the use of an initially stressed drive spring interposed between two members, such as 101 and 103, the desired spark advance may be obtained by causing the inelastic transmission between these members to occur earlier and at the same time an effective spring impulse is obtained for the high speed drive. It is to be noted that the inelastic transmission is effected on direct drive by the direct engagement of members 101 and 103 and on starting drive through the intermediary of lever 102. This lever may be considered as a part of member 103 (since it always moves therewith) which is interposed simply to enable spring 116 to be shifted easily in a lateral direction. The parts which are important for the driving functions are 101 and 103.

The magneto is also characterized by other features of improvement such as the means for shifting the armature actuating mechanism from one to the other of its two positions. The utilization of the hollow hinge shaft of the armature for the reception of connections to transmit a movement from lever 24, which lies wholly without the casing, to the armature actuating mechanism, which

is completely enclosed within the casing, is thought novel and important. The insulation of the lug 77 from the armature is also important, as well as other provisions, which afford definite electrical paths to the ground (housing B) and avoid the possibilities of stray currents passing through bearings and effecting carbonization of the oil therein.

A most important feature of construction relates to the manner in which the stationary elements of the magnetic circuit are arranged and mounted. These elements are secured to the top of member A and are so arranged that the length of the cores 16 is reduced to a minimum.

The frame, which was formerly interposed between the base of coils 19 and the armature and to which the cores were secured, has been eliminated, thus permitting shortening of the core. So also, the cross bars which interconnect the cores and were formerly applied above the coils and below the magnets, have been raised so that the lowest magnet of the stack now virtually rests on top of the secondary coils. Fig. 4 will

make this plain and will show that the distance from the lower face of the lowest magnet to the lower polar face of the cores is only slightly greater than the height of the coils.

A considerable saving in the length of the cores has therefore been effected by the illustrated scheme of supporting the same from the top of member A. That is, the cross bars

66 have the outwardly turned parts 67 which rest upon and are secured to the top of member A. This gives a sufficiently rigid support for the stationary elements of the magnetic field without necessitating any extra length of the cores for the purpose.

The flanges 67 rest on seats on member A, which insures proper location of the polar faces of the cores with respect to the armature. In addition,

the lower magnet 15 may also seat on member A, as shown in Fig. 11 to secure added rigidity of support. The cores 16 also tightly fit within the tubular cores 39 of the primary coils and this contributes to the stability of the support of the magnetic field elements.

The invention has been disclosed herein, in an embodiment at present preferred, for illustrative purposes, but the scope of the invention is defined by the appended claims rather than by the foregoing description.

What we claim is:

1. Armature driving mechanism for a magneto, comprising, two members relatively movable in a direction toward and away from one another and relatively shiftable in another direction from one position to another, one of said members being connected to the armature, means for applying a driving force to the other member to move it in the first named direction, said means operable on the last named member in either of the positions to which said members may be

5 relatively shifted, resilient means associated with said members and arranged to be increased in stress to a substantial degree when said members while in either of said positions are relatively moved by said driving force, and to be increased in stress to a greater degree when said members occupy one of said positions than when shifted into the other position.

10 2. Armature driving mechanism for a magneto, comprising, two members relatively movable in a direction toward and away from one another and relatively shiftable in another direction from one position to another, one of said members being connected to the armature, means for applying a driving force to the other member to move it in the first named direction, said means operable on the last named member in either of 15 the positions to which said members may be relatively shifted, resilient means associated with said members and arranged to be increased in stress to a substantial degree when said members while in either of said positions 20 are relatively moved by said driving force, and means for limiting the degree of relative movement of said members by said driving force and to different degrees according to the position to which said members are relatively shifted, said limiting means effecting an inelastic transmission of force to initially move the armature, such transmission being followed by an elastic transmission from the stressed resilient means to the armature.

25 3. Armature driving mechanism for a magneto, comprising, an assembly consisting of two levers pivotally connected and held against spreading apart beyond a predetermined extent and a drive spring interposed 30 between said levers under a substantially initial stress and tending to hold the levers spread to said extent, a member connected to the armature and engaged by one of said levers, such lever being laterally slidably on 35 said member, means for applying a driving force to the other lever to move it toward the first named lever and increase the tension of said spring, said levers adapted to engage after the tension of said spring has been increased to a predetermined degree and effect 40 an inelastic transmission of force to said member to initiate the movement of the armature, said assembly being bodily shiftable laterally to a position wherein the second 45 lever when moved toward the first lever will first increase the stress of said drive spring but to less than the last named degree and will then directly engage said member and effect an inelastic transmission of force to 50 the armature.

4. In a magneto, an armature, a member connected thereto for moving the same, a drive shaft, and relatively movable members interposed between said drive shaft and first 55 named member by which an inelastic trans-

mission from said shaft to said member may be effected, resilient means arranged to be increased in stress as said second named members are moved to effect said inelastic transmission, said second named members being 60 bodily shiftable from one position to another and initiating said inelastic transmission at an earlier point in the revolution of said shaft when in one position than in the other, and effecting less increase in the stress of said 65 means when said transmission is initiated earlier than when initiated later.

5. In a magneto, of the type wherein an armature is moved into and out of contact with magnetic pole pieces, primary and secondary windings associated with said pole pieces, a normally closed electrical circuit including said primary winding, means operated from the armature at an intermediate point in its flight away from said pole pieces 70 to open said circuit, a drive shaft, an armature actuating mechanism operatively interposed between said shaft and armature and bodily shiftable from one position to another to effect said flight of the armature in 75 either of two ways, said mechanism in each position effecting an inelastic transmission of force from said shaft to the armature to initiate said flight of the armature and including means to impart a spring impulse to the 80 armature following its initial movement, said mechanism when in one of said positions initiating the movement of the armature at an earlier point in the revolution of said shaft 85 than when in the other position and effecting less of a spring impulse insufficient of itself to move the armature to said intermediate point.

6. In a magneto of the type in which an armature is moved into and out of contact with magnetic pole pieces, a hollow shaft to which the armature is fixed, a member fixed to said shaft, a drive shaft, mechanism interposed between said drive shaft and member and bodily shiftable from one position to the 90 other for effecting operation of the armature in either of two ways, means enclosing the aforesaid elements except for one end of said hollow shaft, a lever mounted on said means to control the movement of said mechanism 95 from one position to the other, and connections from said lever to said mechanism including a part disposed in said hollow shaft.

7. In a magneto of the type in which an armature is moved into and out of contact with magnetic pole pieces, a hollow shaft to which the armature is fixed, a member fixed to said shaft, a drive shaft, mechanism interposed between said drive shaft and member and bodily shiftable from one position to the 100 other for effecting operation of the armature in either of two ways, means enclosing the aforesaid elements except for one end of said hollow shaft, a lever mounted on said means to control the movement of said mech- 105

anism from one position to the other, a cam movable by said lever and disposed in and closing said end of the hollow shaft, and means including a rod disposed in the hollow shaft for connecting the cam to said mechanism.

8. In a magneto, of the type in which an armature is moved into and out of contact with magnetic pole pieces, a frame, a hollow shaft mounted therein and to which the armature is fixed, a member fixed to said shaft; an assembly comprising two levers pivotally supported from said shaft for independent swinging movement, a drive spring interposed between said levers and tending to swing them apart, and means for limiting the extent of such swinging movement; said assembly being slideable on said shaft between two extreme positions, means tending to hold said assembly in one of said positions, means on said frame to control the movement of said assembly from one position to the other, operating connections between said means and assembly disposed in said hollow shaft, means for applying a driving force to one of said levers to move it toward the other and stress said spring, the other lever engaging said member, and means controlled by the position of said assembly to effect different degrees of stressing of said spring.

9. A magneto, comprising, a housing frame of insulating material, primary and secondary coils and a condenser mounted in said frame, a metallic housing for closing one end of said frame and adapted for connection to an engine, a spring contact mounted on said frame and engaged by the metallic housing, and an electrical connection between said contact and the ground terminals of said coils and condenser.

10. In a magneto, of the type in which an armature is moved into and out of contact with magnetic pole pieces, a frame of insulating material in which said pole pieces are mounted, relatively movable breaker points, a plunger which is in metallic connection with one of the breaker points and slides in said insulating frame, a metallic housing connected to said frame and into which said armature and plunger extend, means connected to and insulated from the armature for moving said plunger in one direction, and resilient means engaging said housing and plunger for moving the plunger in the other direction and for forming the sole ground connection for the breaker point plunger.

11. A magneto, comprising, a frame of insulating material; a magnetic source, cores, armature, coils, breaker point mechanism and a condenser mounted in said frame; a metallic, lubricant-containing housing connected to said frame and in turn adapted for connection to an engine, said armature extending into said housing, said mechanism includ-

ing a plunger which is in metallic connection with one of the breaker points and also extends into said housing, means connected to and insulated from the armature for moving said plunger in one direction, resilient means connected to said housing for moving the plunger in the other direction and also forming the sole ground connection for said breaker point, a spring contact on said frame adapted to engage said housing, and metallic connections from said contact to the ground terminals of said coils and condenser.

12. In a magneto, a pair of cores, a field magnet extending between the upper ends of said cores and connected thereto, a pair of cross bars one on each side of said magnet and extending from one core to the other and clamped thereto, each cross bar having a part which extends outwardly therefrom with its lower face no lower than the lower face of said magnet, a frame element on which said parts rest and to which they are secured, coils on each core extending from the lower face of said magnet to a point closely adjacent the lower ends of the cores, and an armature movable toward and away from said lower ends.

13. In a magneto, a pair of coils arranged side by side in adjacent relation, a frame element serving to house said coils and being substantially commensurate in height with the length of the coils, a pair of cores, one for each coil and passing axially therethrough with their lower ends projecting slightly beyond the lower face of said element, the upper ends of said cores projecting above the upper face of said element far enough to receive the field magnet, a field magnet interconnecting said upper ends of the cores and having its lower face disposed in closely adjacent relation to the upper ends of said coils, a pair of cross bars located on opposite sides of the core and extending across from one to the other, means for binding said cross bars to the cores, said cross bars having parts extending outwardly therefrom and adapted to rest on and be supported by the upper face of said frame element, and means for securing said parts to said element.

14. In a magneto, of the type wherein an armature is moved into and out of contact with magnetic pole pieces, primary and secondary windings associated with said pole pieces, a normally closed electrical circuit including said primary winding, means operated from the armature at an intermediate point in its flight away from said pole pieces to open said circuit, a drive shaft, an armature actuating mechanism operatively interposed between said shaft and armature, and comprising two relatively movable members and a drive spring held by said members away under a substantial initial stress, said members being relatively moved through a relatively short distance by said drive shaft to increase the stress of said drive

spring and then engaging to effect an inelastic transmission of force to the armature to initiate its flight, such initiation of armature flight being followed by a spring impulse as the stress of said drive spring diminishes to said initial stress, the extent of movement of the armature by the spring impulse being insufficient to move the armature to said intermediate point, the remainder of the armature flight being completed by a transmission of force through said members and spring without yielding of the latter.

CERTIFICATE OF CORRECTION.

Patent No. 1,746,378.

Granted February 11, 1930, to

PHELPS BROWN and TERRENCE G. LOUIS.

It is hereby certified that the above numbered patent was erroneously issued to "Wico Electric Company, of West Springfield, Massachusetts, a corporation of Massachusetts", as assignee of the entire interest in said invention, whereas said patent should have been issued to the inventors said "Brown and Louis, said Louis assignor to Wico Electric Company, of West Springfield, Massachusetts, a corporation of Massachusetts"; page 10, line 127, claim 14, for the word "away" read "always"; and that the said Letters Patent should be read with these corrections therein that the same may conform to the record of the case in the Patent Office.

Signed and sealed this 18th day of March, A. D. 1930.

M. J. Moore,
Acting Commissioner of Patents.
